FOLDING MACHINE

James E. McIntire, Peabody, Mass., assignor to
 United Shoe Machinery Corporation, Borough
 of Flemington, N. J., a corporation of New
 Jersey

Application March 6, 1939, Serial No. 259,940

18 Claims. (Cl. 12—54)

This invention relates to folding machines and is herein illustrated as embodied in a machine for folding the margins of parts of uppers of boots and shoes.

5 In the manufacture of shoes it is common to fold certain margins of the parts of the uppers to provide finished edges which will impart a pleasing appearance to the shoes. There are two well known kinds of edges which are finished by 10 a folding operation. In one case the margin which is folded over is integral with the body portion of the part. In the other case, commonly known as French binding, a strip of binding material is attached to the part along its edge on 15 the display side and is folded over the attached portion and about the edge of the part. In any case, the marginal portion which is folded over, whether integral with the body portion or not, is held in place by an adhesive of some sort which 20 ordinarily is applied to the part prior to the folding operation.

In the folding of parts of the uppers of certain kinds of shoes, concavely curved edges are encountered, the curvatures of which are very 25 sharp so that it is necessary to turn a part having such edges about a small radius. In folding any margin it is desirable that the fold-presser or hammer which presses the fold move in a curved path, the directional components of which are 30 downward and across the line of feed toward the body portion of the work in order that the hammer may properly engage the previously bent up margin, bend it farther and lay it smoothly in place.

35 In order to satisfy these two conditions, namely, that the hammer shall move in the path described and that nevertheless its stem shall not interfere with the turning of the work about a small radius, the hammer or fold-presser of the machine of the present invention is suspended 40 above the work support and moved about an axis located beneath the work support in a curved path the plane of which is transverse to the line of feed of the work. In the illustrated construction, an arm of the frame of the machine 45 overhangs the work support and supports a member having a curved guideway, the axis of the curvature of which is located below the surface of the work-support; and the hammer has an upper 50 wardly extending slender stem having at its upper end a curved guide which is reciprocated in the curved guideway. The hammer is thus suspended above the work support and its operative stroke is such as to press the fold smoothly 55 into place.

This and other features of the invention, including certain details of construction and combinations of parts, will be described as embodied in an illustrated machine and pointed out in the appended claims.

In the drawings,

Fig. 1 is a view, partly in front elevation and partly in vertical longitudinal section, of a machine in which the present invention is embodied;

Fig. 2 is a plan of the machine;

Fig. 3 is a horizontal section on the line III—III of Fig. 1;

Fig. 4 is an end elevation of the machine viewed from the left of Fig. 1;

Fig. 5 is a transverse vertical section showing more particularly parts of the mechanisms for controlling the operation of the feeding means and of the knife;

Fig. 6 is a vertical longitudinal section through a portion of the machine, the folder having been omitted;

Fig. 7 is a perspective of a casting in which the anvil, the folder and the gripper-finger are slidably mounted;

Fig. 8 is a perspective showing more particularly the mechanism for oscillating and reciprocating the hammer and the mechanism for reciprocating the anvil;

Fig. 9 is a detail, principally in section, of part of the mechanism for simultaneously varying the extent of the reciprocation of the hammer and the anvil;

Fig. 10 is a view similar to Fig. 4 but on a larger scale, certain cover plates having been removed and certain parts having been shown in cross-section;

Fig. 11 is a section on the line XI—XI of Fig. 6;

Fig. 12 is a vertical longitudinal section through a portion of the machine viewed from the rear on the line XII—XII of Fig. 10;

Fig. 13 is a view, partly in plan and partly in horizontal section, showing more particularly the hammer-operating mechanism;

Fig. 14 is a detail in plan showing more particularly the anvil and the linkage for varying the extent of its reciprocation;

Fig. 15 is a view, principally in plan, of the lower forward portion of the machine, certain parts having been removed to show more particularly the anvil and its mounting;

- Fig. 18 is a section on the line XVIII—XVIII of Fig. 19, the anvil and its carrier having been omitted;
- Fig. 19 is a section on the line XIX—XIX of Fig. 18, the gripper-finger and most of its actuating mechanism having been omitted;
- Fig. 20 is a view, principally in plan, of the hammer-operating mechanism;
- Fig. 21 is a detail in section showing the knife-operating mechanism;
- Fig. 22 is a section on the line XXII—XXII of Fig. 25 showing the pivotal mounting of the gage and of the lever, manipulation of which raises the presser-foot;
- Fig. 23 is a view, partly in elevation and partly in section, on the line XXIII—XXIII of Fig. 25 showing more particularly the relation of the presser-foot, the gripper-finger and the gage;
- Fig. 24 is a section on the line XXIV—XXIV of Fig. 25;
- Fig. 25 is a vertical section through the presser-foot carrier;
- Fig. 26 is a section on the line XXVI—XXVI of Fig. 29;
- Fig. 27 is a section on the line XXVII—XXVII of Fig. 29;
- Fig. 28 is an end elevation of the lower part of the machine, the cover plate having been removed; and
- Fig. 29 is a section on the line XXIX—XXIX of Fig. 28.
- The machine comprises (Figs. 1 and 2) a frame consisting of a base 40 and an overhanging arm 41, a drive shaft 43 journaled in the overhanging arm and driven by means of a pulley 45 and a belt 46, and a countershaft 47 journaled in the base and driven from the driving shaft 43 by a chain 49. The work is fed intermittently away from the observer, as viewed in Fig. 1, over a table or work-support 177, past a plow or preliminary turning member 235, which turns up the margin of the work as far as a gage 237 will permit, past a knife 361 which may be rendered operative, if desired, to snip the margin of the work, and beneath a presser-foot 231 over an edge of which the turned-up margin of the work is bent still farther by a reciprocating folder 229 to form the fold. The work then passes between a fold-presser or hammer 51 (Fig. 8) and an anvil 163 which first press the fold and then feed the work one step. During the operation of the folder 229 (Fig. 1), the work is held stationary by a gripper-finger 233 which presses the work intermittently against the underside of the presser foot 231. In the operation of the machine the work is fed intermittently by the hammer and the anvil. The anvil moves back and forth in a straight path while the hammer has a four-motion feed, that is, it descends to press the fold 60 against the anvil, then moves forward with the anvil, and then rises and moves back with the anvil into position to descend once more upon the fold which has been formed by the fold-forming instrumentalities.
- The hammer is carried by the overhanging arm of the frame and is oscillated about a horizontal axis which is located beneath the work support, for example, the horizontal axis indicated at x in Fig. 1. The hammer 51 (Figs. 6 and 8) is removably fastened to the lower end of its slender stem 53 by a screw 55, the upper end of the stem being integral with a slide 57 having curved upper and lower faces, said slide being received in a curved guideway in a carrier 59. The curves of the guideway and the slide are struck from a center, such as x (Fig. 1). The hammer-carrier 59 is mounted for horizontal reciprocation on the overhanging arm 41 in a manner which will be explained later. In order to cause the hammer to oscillate, the slide 57 is reciprocated in the curved guideway in the carrier 59. To this end a link 61 connects the slide 57 with the lower end of the substantially vertical arm of a bell-crank lever 63, which is pivoted to the overhanging arm 41 at 65, the substantially horizontal arm of this bell-crank lever being connected by a link 67 with one end of a lever 69 pivoted at 71 to the overhanging arm. The other end of the lever 69 is pivoted at 73 to a small square member, which is slidable in a horizontal guideway in a block 75 (Fig. 6), which in turn is vertically slidable in the overhanging arm 41, said block 75 having a hollow, downwardly extending stem which is slidable in a socket formed in a second slide-block 77. A compression spring 79 rests with its lower end upon the bottom of the socket in the lower block 77 and at its upper end rests against the lower end of a screw 81 threaded into the upper end of the upper block 75. The slide-block 77 is reciprocated to cause oscillation of the hammer 51 by means of a yoke 83, which straddles a cam 85 (Fig. 11) on the driving shaft 43, said yoke being pivoted about a rockshaft 87 carried by the overhanging arm 41 and also being pivoted by a pin 89 to a small block 88, which is slidable in a horizontal guideway in the lower block 77. Rotation of the shaft 43 rocks the yoke 83 about the axis of the shaft 87 and reciprocates the slide-block 77 vertically. Upward movement of the upper slide-block acts to rock the hammer 51 down about the axis indicated at x in Fig. 1 so as to press the fold; and, because of the spring 79, the blow of the hammer upon the work is a yielding one to provide for pieces of work of different thicknesses. The downwardly extending stem of the upper block 75 has integral with it on opposite sides two projections 90, which bear against the wall of an enlarged portion of the socket in the lower block 77, there being above the left-hand projection 90 an overhanging projection 92 integral with the lower block 77 so that, when the block 77 is lowered, the upper block 75 is also lowered.
- As has been explained, the hammer is rocked down upon the work. It is then moved horizontally forward, then rocked up away from the work and finally moved horizontally back to its initial position. The hammer-carrier 59 is mounted for horizontal sliding movement on two parallel rods 91, 93 (Figs. 6 and 8) carried by a removable cap 95 (Fig. 6) which is fastened to the overhanging arm 41 by screws 97, the upper rod 91 having a flattened portion which is received in a horizontal guideway in the hammer-carrier. Horizontal sliding movement of the hammer-carrier 59, without causing binding of the mechanism for oscillating the hammer is permitted by reason of the fact that the downwardly extending arm of the bell-crank lever 63 (Fig. 8) has at its lower end a yoke, the arms of which are spaced considerably apart so that the upper end of the link 61 may slide horizontally on the pin 96 by which the link is pivoted to the bell-crank lever. The hammer-carrier 59 has a horizontal stem rectangular in cross-section which is slidable in a guideway formed in the cap 95 and is reciprocated by means of a well-known form of linkage which may read-

ily be adjusted to vary the extent of the reciprocation of the hammer-carrier. The horizontal stem of the hammer-carrier 59 is shown in cross-section and in plan, respectively, in Figs. 12 and 13, and it will be noted that a gib 98 forms one side of the guideway for the stem and that screw bolts 102 are provided for adjusting the gib to take up for wear. A bell-crank lever 97 (Fig. 8) is pivoted at the end of its horizontal arm at 99 to the outer end of the stem of the hammer-carrier 59 and at the end of its vertical arm at 101 to the lower end of a link 103, the upper end of which is pivoted to the outer end of an arm 105, the hub of which is pinned to the rockshaft 87, said rock-15 shaft being rocked by a yoke 107 which is fast to the rockshaft and straddles a cam on the driving shaft 43.

In order to control the movement of the bell-crank lever 97 and thereby vary the extent of the reciprocation of the hammer-carrier 59, said bell-crank lever is pivoted at 109 to the lower end of a link 111, the upper end of which is pivoted to the upper end of an arm 113 which is fastened to one end of a manually operated feed-control rockshaft 115 carried by the overhanging arm 41. This rockshaft has at its right-hand end (Fig. 8) a member having two arms 118, 121. The arm 121 serves to control the reciprocation of the anvil, as will later appear. The arm 119 is pivoted to the upper end of a treadle rod 123, the lower end of which is pivoted to a treadle, not shown, which is held up by a spring, also not shown. When the feed-control shaft 115 is rocked to bring the pivot at the upper ends 35 of the links 111, 113 into line with the pivot 99, the bell-crank lever 97 will be rocked idly about its pivot 99; but when the aforesaid pivots are out of line, reciprocation will be imparted to the hammer-carrier 59, the extent of this reciprocation depending upon how much the aforesaid pivots are out of line. The arm 121 on the rockshaft 115 is pivoted to the upper end of a link 125, the lower end of which is pivoted to an arm 127 on a second rockshaft 129 mounted in 40 the base of the machine, rocking of which controls the extent of reciprocation of the anvil through a link mechanism, later to be described. When the treadle rod 123 is moved up or down, both shafts 115, 129 will be rocked equally, the 45 construction being such that the extent of reciprocation of the hammer is always the same as that of the anvil. In order to predetermine the limits of such reciprocation—that is, the limits of feed movement imparted to the work—a second arm 131, carried by the rockshaft 129 and integral with the arm 127, is adapted to engage either one of two stops in the form of eccentric pins 133, 135 carried at the inner ends of short rods 137, 139 which are rotatable in bushings, 50 said bushings being integral with a small plate 141 (Figs. 1 and 9) fastened to the frame of the machine. The rods 137, 139 have, respectively, knurled heads 143, 145 fastened to them by pinch-screws; and each knurled head carries a pawl to 55 hold it in any angular position into which it may be moved. Since the pawls are alike only one will be described. Referring to Fig. 9, the pawl 147 of the knurled head 145 is in the form of a bell-crank lever pivoted at 149 to the head and 60 normally held in a selected notch 151 in the plate 141 by a spring 153. Both knurled heads 143, 145 and the plate 141 with two sets of notches, one for each head, are shown in Fig. 1. By turning the heads 143, 145, the extent of the 65 maximum and minimum feed movements capable

of being imparted to the work by manipulating the treadle rod 123 may be predetermined. It should be particularly noted that the hammer moves in its descent in a curved path, the two components of movement of which are respectively downward upon the fold and inward toward the body portion of the work, and that the hammer is suspended by a slender stem from the overhanging arm. The curved path of movement ensures proper pressing of the fold about 10 the line determined by the edge of the presser-foot about which the fold is formed by the folder; and the slender upwardly extending stem permits operation upon sharply concave curves of 15 small radii.

The anvil 163 (Fig. 8) is fastened to an anvil-carrier 165, said carrier being slidable upon a horizontal rod 167 which is held in a casting 169 (Fig. 7), said casting being fastened to the base of the machine by dowel pins and by screws which 20 pass through the four holes 171. One end of this rod 167 is received in the hole 173 and the other end in an alined hole at the other end of the casting, as best shown in Fig. 10. In this latter figure, the reason for the sockets in the 25 ends of the rod 167 appears. These sockets receive pins 175 which help to hold the work table 177 removably in place. The anvil-carrier 165 is reciprocated from the countershaft 47 through an adjustable link mechanism similar to that 30 through which the hammer-carrier is reciprocated. Referring more particularly to Fig. 10, a cam 179 on the countershaft 47 is straddled by a yoke 181, said yoke being pivoted about the axis of a pin 183, which is driven into the yoke 35 and is received in a hole 185 (Fig. 7) in the casting 169. Referring again to Fig. 10, pivoted at its lower end to the yoke 181 is a link 187, the upper end of which is pivoted to the substantially vertical arm of a bell-crank lever 189, the 40 substantially horizontal arm of which is pivoted at 196 to an ear on the underside of the anvil-carrier 165. Pivoted about a pivot 191, which is rotatable in a bore in the frame of the machine, is the upper end of a link 195, the lower end of 45 which is pivoted at 197 to the upper end of a link 199, the lower end of which is pivoted to the outer end of an arm 201, the hub of which is fast to one end of the rockshaft 129. A link 203 is pivoted at its lower end about the pivot 50 197 and at its upper end about a pivot 205 carried by the bell-crank lever 189. When now, the shaft 129 is rocked to cause the pivots 196 and 197 to be in alinement, oscillation of the yoke 55 181 will rock the bell-crank lever idly; but when the shaft 129 is rocked to move the pivots 196, 197 out of alinement, the anvil-carrier 165 will be reciprocated. The rockshaft 129 (Fig. 8), as has been explained, is connected to the rock-shaft 115; and when the treadle rod 123 is manipulated the two shafts are rocked in unison so that the extent of feed movement of the hammer is 60 always equal to that of the anvil.

The anvil-carrier 165 (Figs. 12 and 15) has an upper portion which is substantially rectangular in cross-section and is slidable between two gibs 207 adjustably mounted in a recess in the casting 169, and each adjustably mounted toward the anvil-carrier 165 by means of two screws 209, the four screws being threaded, respectively, through the 65 holes 211 (Fig. 7) in the opposite walls of the casting and abutting in pairs the gibs 207 (Fig. 15). In order to hold the gibs firmly against the ends of the adjusting screws 209, two screws 213 are provided, the stems of which pass re- 70 75

- spectively through the holes 215 (Fig. 7) in the opposite walls of the casting 169 and are threaded into the gibs. By this construction means is provided for taking up wear of the parts.
- 5 The work support or table 171 (Figs. 1 and 2) is made in two parts, being split lengthwise of the machine, as indicated in Fig. 2, so as to comprise a front part and a rear part. These two parts have each a downwardly extending lug through 10 which, and into holes in the opposite ends of the rod 167 (Fig. 10), the pins 175 pass. Two latch rods, one of which is shown at 217 in Fig. 4 and both of which 217, 219 are shown in Fig. 16, are pivoted at one of their ends, respectively, about 15 pivots 221, 223 carried by the lug of the rear part of the table. The other ends of the latch rods may be swung into and out of open-sided slots in the lug of the front part of the table and have, respectively, thumb nuts 225, 227 at their 20 ends. The table is thus firmly clamped in place upon a part of the base of the machine which is received between the two downwardly projecting lugs of the table, and the table may readily be removed and replaced when desired. The table 25 has an opening near its center to expose certain members, including the anvil which has just been described, so that they may engage the underside of the work.
- Referring to Figs. 23 to 25, in which a piece 30 of work 100, such as a leather shoe part, is shown in process of being operated upon, the work is intermittently held stationary during the operation of the folder 229 by the action of the presser-foot 231 and the gripper-finger 233, later 35 to be described, which is moved up at the proper time to grip the work against the lower face of the presser-foot, said gripper-finger being moved down at the proper time to permit the work to be fed. The work is fed over the table away from the observer (Fig. 25) with its margin engaging 40 the plow 235, a gage 237 which extends over the plow limiting the extent of the margin which is turned up and hence the width of the fold. Just ahead of the plow, in the direction of feed movement, the presser-foot 231 engages the work; and over the edge of this presser-foot the upturned margin of the work is bent by the folder 229. The presser-foot 231 and the gage 237 are mounted in a readily removable casting 238, which is fastened to the cap 95 by screws 240. The stem of the gage 237 (Fig. 22) is mounted upon a pivot 239 carried by the casting 238, has at its right-hand end a finger-piece 241 by which that end may be depressed, and is normally held 50 in the position shown by a spring 242. The finger-piece 241 is located below a second finger-piece 243 on a lever 245, which is also mounted on the pivot 239, depression of the finger-piece 243 serving to rock the lever 245 clockwise and thereby raise the presser-foot in a manner presently to be described. It will be noted that, when the finger-piece 243 is depressed to raise the presser-foot, the finger-piece 241 is also depressed to raise the gage 237, such raising of these two 60 members serving to facilitate presentation of a piece of work to the machine. The left-hand end of the lever 245 engages the underside of a roll 247 which is rotatable on a horizontal pivot 249 carried at the lower end of a vertically slidable presser-carrier 251. The presser-foot 231 has an upwardly extending stem provided near its middle with a hub having a hole to receive the pivot pin 240, the part of the stem of the presser-foot which is above the pivot pin having 70 at its upper end a cam-arm which is held in en-

gagement with the underside of a stationary but adjustable crank-pin 255 by a small spring-pressed plunger 257. The crank-pin 255 (Fig. 20) is carried at the end of a headed pin 256 which is rotatable in the casting 238 and is held 5 in adjusted angular position by a set screw 260 (Fig. 24). The spring 259, which acts upon the plunger 257, is located in a socket formed in a plate 261 fastened to the casting 238, and the tension of the spring may be varied by turning 10 a screw 263. The presser-carrier 251 has fastened in a bore in its upper part the lower end of a rod or stem 265, said rod being vertically slidable in a sleeve 267, the upper part of which is slidable and rotatable in a bore formed in a part 15 of the casting 238, and the lower part of which is threaded into a sleeve 269 which is held from rotation but is vertically slidable in a guideway, one side of which is the inner face of the plate 261. Threaded on the upper end of the rod 265 20 are an adjusting nut 271 and a check-nut 273 to limit the extent of the downward movement of the presser-carrier. A spring 242, which rests upon the presser-carrier 251, engages with its upper end a washer 244, which in turn engages 25 the lower end of the sleeve 269. With the above construction the vertical position of the presser-foot 231 may be varied by turning the adjusting nut 271; and the tension of the spring 242 may be varied without varying the vertical position of 30 the presser-foot by turning the sleeve 267 by means of the hexagonal head formed at its upper end. The angular position of the presser-foot may be varied by turning the pin 256.

Referring more particularly to Figs. 16 to 19, 35 the mounting of the folder 229 will be described. The operative portion of the folder is a slender finger. The stem (Fig. 19), however, is in the form of a comparatively thin bar much wider than the slender finger, said bar being bevelled 40 along its opposite sides, as indicated at 275. The stem is slidable in a dovetailed guideway formed partly in a block 277 and partly in a second block 279. The block 279 is clamped adjustably to the block 277 by a screw 281, the stem of which passes through a hole in the block 279 and is threaded into the block 277. In order to space the blocks properly, two set screws 283, one on each side of the clamping screw 281, are threaded through the block 279 and abut the block 277. The two 50 blocks thus held together are received in a guideway 285 (Fig. 7) in the casting 169 and are fastened in adjusted horizontal position by a screw 287 (Figs. 16 and 19), the stem of which is smaller than the hole 289 (Fig. 7) in a wall of 55 the casting 169 through which it passes, and the head of which is smaller than the countersink 291. This screw 287 (Figs. 16 and 19) is threaded into the block 277 and clamps this block firmly to the wall of the casting 169. When the screw 60 has been loosened, the block 277, and with it the block 279, may be adjusted horizontally so as to adjust the folder transversely of the line of feed. To facilitate such adjustment, a pin 293, which is rotatable in a hole 295 (Fig. 7) in a wall of 65 the casting 169, has at its inner end an eccentric 297 (Fig. 16) which is received in a socket in the block 277 so that, when the pin 293 is turned, the folder-carrier consisting of the blocks 277, 279 is adjusted transversely of the direction of feed 70 movement of the work. The folder is reciprocated in the inclined guideway formed partly in the block 277 and partly in the block 279 by a link 299, the upper end of which is pivoted to the lower end of the stem of the folder. The lower 75

end of this link is pivoted at 301 to a link 303, which in turn is pivoted at 305 to the upper end of a link 307, the lower end of which is pivoted to the tail of a yoke 309, said yoke being pivoted at 311 to the frame of the machine and being actuated by a cam 313 on the countershaft 47. The construction and mounting of the gripper-finger 233, which intermittently grips the work against the presser-foot, will now be described, 10 it being remembered that when the machine has been stopped it is desirable to pull down the gripper-finger preparatory to presenting a piece of work to the machine. Referring particularly to Figs. 26 to 29, the gripper-finger 233 is fast 15 to the upper end of a rod 315 which is vertically slidable in a bore 317 (Fig. 7) formed in the casting 169. Referring to Fig. 28, the lower end of rod 315 carries a small block 316 having a horizontal slot in which is slidable a small square block 318, said block being pivoted at 319 to the horizontal arm of a three-armed lever 321, the lower arm of which is pivoted to one end of a link 323. The other end of this link is pivoted to the lower end of an upwardly extending bent 20 lever 325 at the upper end of which is a hub, rotatably mounted on the same pin 183 about which the yoke 181, which acts to reciprocate the anvil, is pivoted. The three-armed lever 321 is also pivoted at 327 to one end of a short arm 25 329, the other end of which is fast to the inner end of a pin 331 which is rotatable in a hole 333 (Fig. 7) in a wall of the casting 169 and extends out through said hole. Fast to the outer end of the pin 331 outside of the wall of the casting 169 30 (Fig. 29) is a two-armed lever 335, the hub of which is pinned to the outer end of the rotatable pin 331. A spring-pressed plunger 337, acting against the upper end of the upper arm of the lever 321, acts through said lever and the link 323 35 to hold the bent lever 325 against a cam 339 on the countershaft 47. A second spring-pressed plunger 341, mounted in a cap 343 fastened to the frame by screws 345, tends to swing the lever 335 clockwise, as viewed in Fig. 28, as far as an adjustable stop-pin 347 will permit and holds this 40 lever in the position shown. Since the lever 335 is thus held, the pivot 327 is held immovable, and rotation of the shaft 47 with its cam 339 rocks the three-armed lever 321 about the pivot 327 and reciprocates the gripper-finger 233 vertically. When now, with the machine at rest, it is desired to lower the gripper-finger 233 to facilitate the presentation of a piece of work to the machine, the operator has merely to push in a 45 pin 349, which is slidably mounted in the cap 343 and the inner end of which contacts with the upper end of the upper arm of the lever 335. This rocks the lever 335 counterclockwise (Fig. 28) about the fixed pivot 331; and, due to the linkage 50 described above, pulls down the gripper-finger, the three-armed lever 321 moving bodily downward. The casting 169, as has been explained, is fastened to the frame by dowel pins and screws which pass through holes 171 in a wall of said casting. The dowel pins (Figs. 26 and 27) are indicated at 351 and the screws at 353.

The knife 361 (Fig. 25) is fast to a bent lever 363 pivoted about a rod 365 about which it may be caused to oscillate when desired so as to snip 55 the margin of the work. The knife on its cutting strokes cooperates (Fig. 24) with an adjacent vertical flat face of the plow 235 to shear the work. The upper end of the bent knife-lever 363 (Fig. 25) is connected to the lower end of a vertical link 366 by a ball joint; and the upper

end of this link is connected by a second ball joint with an arm 367, the hub of which is loosely mounted on the rockshaft 87 (see also Fig. 8 from which the link 366 has been omitted). When, therefore, the arm 367 is oscillated, the knife 361 is oscillated to snip the margin of the work. This arm is normally held stationary in its lowered position by a spring 368 (Figs. 8 and 21) but can be connected when desired to a constantly oscillating arm 369. For this purpose, the outer ends 10 of the arms 367, 369 are provided with open-ended slots which face each other, and the outer end of a small lever 371 can be moved entirely into the slot in the arm 367 (in which case the knife is stationary and inoperative) or into the 15 position shown in Fig. 25 (in which case the knife is oscillated and operative). The arm 371 (Fig. 24) is forked at its inner end and is pivoted to the arm 367 by a pin 373 which passes through the arms of the fork and through a vertical hole 20 375 (Fig. 8) in the arm 367. The hub of the actuating arm 369 (Fig. 24) is loose on the rockshaft 87 and has a depending portion which is held against a cam 377 on the driving shaft 43 by means of a spring 379. The small forked lever 25 371 (Fig. 21), the angular position of which determines whether the knife is being oscillated, has one arm of its fork elongated to extend between the end of a spring-pressed plunger 381 and the end of a push-rod 383. The other end 30 of the push-rod 383 (Fig. 1) is connected by a link 385 with the upright arm of a bell-crank lever 387 which is pivoted at 389 to the overhanging arm 41. To the outer end of the horizontal arm of the bell-crank lever is pivoted the 35 upper end of a treadle-rod 391, the lower end of which is connected to a treadle (not shown). A tension spring 393, which is stronger than the compression spring 395 (Fig. 21) which acts against the spring-pressed plunger 381, normally 40 swings the bell-crank lever 387 counterclockwise (Fig. 1) to push the rod 383 to the left and thereby swing the small control lever 371 (Fig. 21) counterclockwise sufficiently so that the outer end of this small lever is entirely within the open-45 ended slot in the outer end of the arm 367. Normally, then, this arm remains stationary and the knife is held stationary in inoperative position. When, however, the treadle-rod 391 (Fig. 1) is pulled down by depressing the treadle (and this 50 is the position of parts shown in the drawings), the push-rod 383 is pulled to the right and the spring-pressed plunger 381 swings the small control lever 371 clockwise (Fig. 21), whereupon, when the constantly oscillating arm 369 swings 55 down until the open-ended slot in its outer end is in register with the open-ended slot in the outer end of the arm 367, the outer end of the small lever 371 enters the slot in the constantly oscillating arm 369 so that the arm 367 is oscillated and, 60 through the link 366 and the bent lever 363, oscillates the knife 361.

Having described my invention, what I claim as new and desire to secure by Letters Patent of the United States is:

1. A machine of the class described comprising in combination, a work-support over which the work is fed, fold-forming means, and fold-pressing means, said fold-pressing means being supported from above the work-support for 70 movement in a curved path about an axis located beneath the level of the surface of the work-support.

2. A machine of the class described comprising in combination, a work-support over which the 75

- work is fed, fold-forming means, an arm which overhangs the work-support, fold-pressing means, and mechanism carried by the overhanging arm for oscillating the fold-pressing means in a curved path the plane of which is transverse to the line of feed of the work.
3. A machine of the class described comprising in combination, a work-support over which the work is fed, fold-forming means, an arm which overhangs the work-support, fold-pressing means, and mechanism carried by the overhanging arm for oscillating the fold-pressing means in a curved path about an axis which is located beneath the level of the work-support.
- 15 4. A machine of the class described comprising in combination, a work-support over which the work is fed, an arm overhanging the support, fold-forming means, and fold-pressing means, said fold-pressing means being mounted in the overhanging arm for movement in a curved path about an axis which is located beneath the level of the work-support.
- 25 5. A machine of the class described comprising in combination, a work-support over which the work is fed, an arm overhanging the support, fold-forming means, fold-pressing means, said last-named means comprising a hammer having a slender upwardly extending stem, and means mounted in the overhanging arm for oscillating the hammer in a curved path the plane of which is transverse to the line of feed of the work.
- 35 6. A machine of the class described comprising in combination, a work-support over which the work is fed, fold-forming means, fold-pressing means, said fold-pressing means comprising a hammer having an upwardly extending slender stem, and means for oscillating the hammer in a curved path, said means including a slide block rigid with the stem of the hammer and a curved guideway in which the block is slideable.
- 40 7. A machine of the class described comprising in combination, a work-support, fold-forming means, a hammer and anvil which cooperate to press the fold and to feed the work, an overhanging arm by which the hammer is carried, means for oscillating the hammer in a curved path the plane of which is transverse to the line of feed of the work, and means for reciprocating the hammer and the anvil in the line of feed of the work.
- 50 8. A machine of the class described comprising in combination, a work-support, fold-forming means, fold-pressing means including a hammer having a slender stem, an arm overhanging the work-support, a hammer-carrier mounted for sliding movement in the overhanging arm in a path parallel to the direction of feed movement of the work, said hammer-carrier having a curved guideway extending at right angles to the direction of feed movement of the work, and a curved slide rigid with the stem of the hammer and slideable in the guideway.
- 55 9. A machine of the class described comprising in combination, a work-support, fold-forming means, fold-pressing means including a hammer having a slender stem, an arm overhanging the work-support, a hammer-carrier mounted for sliding movement in the overhanging arm in a path parallel to the direction of feed movement of the work, said hammer-carrier having a curved guideway extending at right angles to the direction of feed movement of the work, a curved slide rigid with the stem of the hammer and slideable in the guideway, means including a spring for oscillating the hammer, and positively

actuated means for reciprocating the hammer-carrier.

10. A machine of the class described comprising in combination, a work-support, means for forming a fold in the work, and means for feeding the work and pressing the fold, said feeding and fold-pressing means including a hammer and an anvil, a hammer-carrier and an anvil-carrier, each having rigid with it a slide, two substantially horizontal guideways in which the slides are respectively received, one wall of each guideway consisting of a gib, and means for adjusting the gibs.

11. A machine of the class described comprising in combination, a work-support, fold-forming means, means for intermittently feeding the work and means for pressing the fold, said feeding means including upper and lower members which grip the work and advance it one step at a time, separate mechanisms for varying the extent of feed movement of the upper and lower members respectively, treadle-controlled means normally holding the mechanisms in a position to cause a given extent of feed movement to be imparted to the work, manipulation of said treadle-controlled means acting to change the extent of said feed movement, and two manually adjustable members capable of being adjusted into various positions to limit the maximum and minimum extent of said feed movements.

12. A machine of the class described comprising in combination, a work-support, fold-forming means, means for intermittently feeding the work and means for pressing the fold, said feeding means including upper and lower members which grip the work and advance it one step at a time, mechanisms for varying the extent of feed movement of the upper and lower members respectively, treadle-controlled means normally holding the mechanisms in a position to cause a given extent of feed movement to be imparted to the work, manipulation of said treadle-controlled means acting to change the extent of said feed movement, means for limiting the maximum and minimum extent of said feed movements, said means including a pair of easily accessible rotary members, a stationary notched plate, and pawls on said members adapted to engage selected notches in the plate.

13. A machine of the class described comprising in combination, a work-support, work-feeding, fold-forming and fold-pressing instrumentalities, a casing detachably fastened to a part of the frame of the machine, and a spring-pressed presser-foot carried by the casing and removable and replaceable with it.

14. A machine of the class described comprising in combination, a work-support, work-feeding, folding and fold-pressing instrumentalities, a presser-foot having a stem, a spring for urging the presser-foot toward the work-support, a sleeve through which the stem is slideable, said sleeve being rotatable but held from longitudinal movement, a stop threaded on the stem and held in contact with the sleeve by the spring, and means whereby rotation of the sleeve varies the tension of the spring while maintaining the position of the presser-foot unchanged.

15. A machine of the class described comprising in combination, a work-support, work-feeding, folding and fold-pressing instrumentalities, a presser-foot, a casing in which the presser-foot is vertically slideable, a threaded sleeve also vertically slideable in the casing, a second sleeve the

- upper part of which is rotatable in the casing and the lower part of which is threaded into the first-named sleeve, a stem fastened at its lower end to the presser-foot and extending slidably up through the first-named sleeve, a spring between the presser-foot and said first-named sleeve, and a nut threaded on the upper end of the stem in position to contact with the top of the second-named sleeve.
16. A construction according to claim 15 in which means are provided for detachably fastening the casing to the frame of the machine whereby the casing with the presser-foot and its mounting may be readily removed and replaced.
17. A machine of the class described comprising in combination, a work-support, feeding, folding and fold-pressing instrumentalities, a presser-foot, a gripper-finger for intermittently cooperating with the presser-foot to grip the work, an actuating lever connected with the grip-
- per-finger, a pivot, means for oscillating the lever about the pivot to reciprocate the gripper-finger, and manually operable means for lowering the pivot and with it the actuating lever and the gripper-finger.
18. A machine of the class described comprising in combination, a work-support, feeding, folding and fold-pressing instrumentalities, a presser-foot, a gripper-finger for intermittently cooperating with the presser-foot to grip the work, an actuating lever to one arm of which the gripping finger is pivoted, a pivot for the lever, means connected with a second arm of the lever for oscillating the lever about the pivot, means for holding the pivot stationary during the oscillation of the lever, and means for lowering the pivot when the machine is at rest to lower the lever and with it the gripper-finger.

JAMES E. McINTIRE. 20
